US00D990121S

(12) **United States Design Patent** (10) Patent No.: **US D990,121 S**
(45) Date of Patent: ** Jun. 27, 2023

(54) **SOLE**

- (71) Applicant: **Reebok International Limited**, Altrincham (GB)
- (72) Inventors: **Dustin Simone**, Mansfield, MA (US); **Isaac Toonkel**, Dorchester, MA (US)
- (73) Assignee: **Reebok International Limited**, Altrincham (GB)
- (**) Term: **15 Years**
- (21) Appl. No.: **29/851,616**
- (22) Filed: **Aug. 30, 2022**

(57) **CLAIM**

The ornamental design for a sole, as shown and described.

DESCRIPTION

FIG. 1 is a front side perspective view of a sole showing the claimed design;

FIG. 2 is a rear side perspective view thereof; and,

FIG. 3 is a side view thereof.

The dashed broken lines in the figures show portions of the sole that form no part of the claimed design. The dot-dash broken lines in the figures show boundaries that form no part of the claimed design.

1 Claim, 3 Drawing Sheets

See application file for complete search history.
